1

This invention relates to an improvement in television systems, and more particularly to an improvement in a television receiver for receiving a radio frequency carrier which has been frequency modulated by the television signals.

In conventional television systems the video or image and synchronizing signals are transmitted as modulations of one carrier frequency while the accompanying audio or sound signals are transmitted as a modulation of a separate carrier, generally positioned slightly above the video or image carrier. It is normal practice to amplitude modulate the video carrier and to frequency modulate the audio frequency carrier. In the amplitude modulation of the radio frequency carrier by the video signal, it is standard practice to control the carrier amplitude in such a way that full carrier amplitude (or 100%) is transmitted during the presence of synchronizing signals only. Full black in the subject is generally transmitted at approximately 75% of maximum carrier amplitude, and full white in the picture is normally transmitted at approximately zero amplitude of the carrier (when direct current insertion is employed). Signal transmission in this manner is necessary in television in order that the background or average light intensity may be transmitted to the receiver and in order that the synchronizing signals may be separated from the image signals by amplitude selection or other appropriate means.

The audio signals are generally transmitted as a frequency modulation of the carrier provided for that purpose, and are detected by appropriate discrimination circuits in the television receiver. Since the audio and video signals are transmitted as modulations of separate carriers, it is common practice in a television receiver to employ a single local oscillator, which when beat against the two received radio frequency carriers produces two separate intermediate frequencies. One of these is a frequency modulated intermediate frequency carrier and includes the audio information, whereas the other is an amplitude modulated intermediate frequency carrier and includes the video information.

In the present invention provision is made whereby both the video and the audio signals are transmitted by frequency modulation of separate radio frequency carriers, and when this is done in accordance with the present invention, the conventional video signal present at the transmitter is used for frequency modulating an appropriate carrier.

In the present invention two different types of

2

receiving circuits may be employed. In one instance the full frequency deviation produced by the modulation video signal is represented by a single intermediate frequency channel and a single discriminator is used so that at the output of the discriminator a complete composite television signal will be present including the image signals, the blanking and the synchronizing signals.

- 10 In another form of the present invention, separate intermediate frequency channels are employed in the receiver, one for passing the frequency deviations representing the image portion of the received signals and the other for passing 15 only the frequency deviations representing the synchronizing portion of the received signals. In this particular form of the present invention, the complete composite video signal is received as a frequency modulation of a single carrier, but 20 by providing separate intermediate frequency channels having different band pass characteristics, the image signals and the synchronizing signals may be separated according to the frequency deviations of the intermediate frequency 25 carrier. When such a system is employed, two separate detectors or discriminators are used, one for responding to the frequency deviations occurring within the image intermediate frequency channel and the other for responding to frequency 30 deviations occurring within the synchronizing intermediate channel frequency. When separate intermediate frequency channels are provided for the image and synchronizing signals, complete and convenient separation of these signals is possible. It is, therefore, possible to cause the receiver to respond to synchronizing impulses of 35 proper amplitude while at the same time the receiver is unresponsive to transient conditions or undesired disturbances which produce deviations less than maximum deviations produced by 40 the synchronizing impulses.

In the present invention the audio signals may still be transmitted as a frequency modulation of a separate radio frequency carrier, and for the 45 transmission of these signals through the receiver a separate intermediate frequency amplifier channel may be provided.

It is, therefore, one purpose of the present invention to provide means for transmitting video signals as a frequency modulation of a radio frequency carrier.

Another purpose of the present invention resides in the provision of a television receiver responsive to frequency modulations of a radio frequency carrier in which the frequency modula-

tions are produced in accordance with the television video signals.

Still another purpose of the present invention resides in the provision of a television receiver for receiving a frequency modulated carrier, the frequency deviations of which are produced in accordance with composite video signals, together with means for detecting and separating the image signals from the synchronizing signals.

A still further purpose of the present invention resides in the provisions of means in a television receiver for receiving a frequency modulated radio frequency carrier in which the frequency deviations are produced by a composite video signal and in which the receiver includes two intermediate frequency channels, the band pass of one being sufficient to accommodate the frequency deviations representing the image signals, and the band pass of the other being chosen to accommodate the frequency deviations representing the synchronizing signals.

Still another purpose of the present invention resides in the provision of means in a television receiver for receiving a video signal frequency modulated radio frequency carrier in which the various intermediate frequency band pass circuits are so designed that over-modulation or excessive frequency deviation do not produce any undesired or erroneous results.

Various other advantages and purposes of the present invention will become more apparent to those skilled in the art from the following detailed description, particularly when considered in connection with the drawings, wherein like reference numerals represent like parts and wherein:

Figure 1 diagrammatically represents one form of the present invention;

Figure 2 shows a graph and curves used in explaining the operation of the system shown in Figure 1;

Figure 3 shows a diagrammatic modification of the present invention;

Figure 4 shows a graph and curves used in explaining the operation of the system shown in Figure 3;

Figure 5 shows curves representing one undesired result that will take place under one set of circumstances;

Figure 6 shows curves representing another undesired result that will take place under another set of circumstances; and

Figure 7 shows curves representing desired response under conditions of over-modulation.

Referring now to Figure 1, there is shown schematically a television receiver including a radio frequency tuner 10 to which signals received upon an appropriate antenna 12 (or by way of other communication channel) are supplied. A local oscillator 14 is also provided, the frequency of operation of which may be altered in accordance with the radio frequency tuning of the receiver. The received signals and the oscillations from the oscillator 14 are supplied to a mixer in order to produce an intermediate frequency carrier which is applied to an intermediate frequency amplifier 16. If the audio signals which accompany the video signals are transmitted as modulations of a separate radio frequency carrier, the audio intermediate frequency carrier may be supplied to appropriate amplifiers and demodulators over conductor 18.

Since the present invention is not concerned with the particular audio system employed, details of that system are not shown herein.

The output from the video intermediate frequency amplifier is then applied to a discriminator network 20 (preceded by a limiter, if desired), and the resulting video signals are, in turn, applied to an appropriate video amplifier 22. The discriminator also applies signals to a synchronizing signal separator 24 in order that the synchronizing signals may be separated from the image signals thereby to control the operation of horizontal and vertical deflection generators 26. The amplified video signals as supplied by the amplifier 22 are applied to the control electrode of an image producing tube or "Kinescope" 28 in order to modulate the current intensity of a cathode ray beam developed therein. In order that the cathode ray beam may be caused to scan a target surface or luminescent or fluorescent screen, energy from the horizontal and vertical deflection generators 26 is applied to a deflection yoke 30 associated with the image tube.

As stated above, the television receiver is designed to receive a radio frequency carrier that has been frequency modulated by the composite video signal series. In order to clearly explain the operation of the system represented by Figure 1, reference is now made to Figure 2 of the drawings.

It will be assumed, for example, that the center frequency of the radio frequency carrier is 104 megacycles, with deviation limits extending 4 megacycles on each side of the carrier center as shown in Figure 2. Therefore, the lower deviation limit of the carrier is approximately 100 megacycles, whereas the upper deviation limit is 108 megacycles.

It will also be assumed that the peaks of the synchronizing impulses are transmitted at approximately the upper deviation limit and that full white in the image is transmitted at approximately the lower deviation limit. If a standard composite video signal series is used to frequency modulate the radio frequency carrier, then full black in the image will be represented by 106 megacycles. Under these conditions a band of 6 megacycles is provided for the transmission of the image signals and, similarly, a band of 2 megacycles is provided for the transmission of the synchronizing signals.

If under these conditions the local oscillator at the receiver operates, for example, at 90 megacycles, a complete intermediate frequency band of 8 megacycles is required for the transmission of the intermediate frequency carrier, and this band extends from 10 megacycles as a lower deviation limit to 18 megacycles as an upper deviation limit. Full black in the image (or the blanking impulses) occurs at 16 megacycles in the intermediate frequency channel in the assumed exemplary system.

For responding to these frequency deviations a discriminator must be provided having a sufficient frequency band width to respond to the full 8 megacycle deviation band in a substantially linear fashion. A desired discriminator response curve is shown in Figure 2, and when frequency deviations from the intermediate frequency amplifier channel are applied to the discriminator, a series of composite video signals such as represented in Figure 2 may be produced. It is desirable that the discriminator respond substantially linearly to frequency deviations occurring between 10 and 18 megacycles, and it may also be desirable under some circumstances that the discriminator be non-responsive to signals occur-

ring below 10 megacycles or above 18 megacycles. A discriminator having such a response curve is shown and described in U. S. Letters Patent No. 2,413,913, issued to Vernon J. Duke on Jan. 7, 1947.

It may be seen, therefore, that when a television receiver such as that represented in Figure 1 is provided for the reception of a frequency modulated carrier, a composite video signal may be produced, as shown in Figure 2, which includes the image signals, the blanking signals and the synchronizing signals in their proper intensity, and having proper values with respect to each other, provided no over-modulation occurs. To produce such a result it is merely necessary to frequency modulate a radio frequency carrier by the presently used video signals, and when such signals are received and are applied to an appropriate discriminator, a video signal series will be produced which may be employed for producing a visual image in a manner similar to the present amplitude modulation receivers.

In a system as described above, some form of synchronizing separation circuit must be provided for separating the synchronizing impulses from the image signals and, in addition, a relatively wide band intermediate frequency amplifier channel and discriminator must be provided.

In a modification of the present invention it is proposed to provide two separate intermediate frequency channels in the receiver (in addition to the sound channel), the channels being related to each other in such a manner that a single radio frequency carrier that has been frequency modulated by the video signal may be received. In this respect, reference is now made to Figure 3 wherein a receiver diagram is shown which includes a radio frequency tuner and mixer 10 as in Figure 1 to which is applied energy from an appropriate antenna 12, for example. An oscillator 14 is also provided for heterodyning with the received carrier signals to produce intermediate frequency carriers. The frequency deviations which are produced as a result of the television image signals are then applied to the image intermediate frequency amplifier 40, while the frequency deviations representative of the synchronizing signals are applied to the synchronizing signal intermediate frequency amplifier 42. The intermediate frequency representative of the accompanying audio signals may be applied to proper audio channels by conductor 18, as explained above in reference to Figure 1.

The output from the image intermediate frequency amplifier 40 is applied (after limiting, if desired) to an image discriminator 44 which in turn supplies image signals to an appropriate image signal amplifier 46. The synchronizing intermediate frequency amplifier supplies signals to a synchronizing signal discriminator 48 (also after limiting, if desired) and the output of this discriminator is applied as control signal impulses upon the horizontal and vertical deflection generators, conventionally shown at 50. The horizontal and vertical deflection generators supply energy to a deflection yoke 30 for properly deflecting a cathode ray beam developed within the "Kinescope" or image producing tube 28, and the current intensity of the cathode ray beam is modulated by the output from the image amplifier 46.

To describe the operation of the system shown in Figure 3, reference is now made to the graphs and curves shown in Figure 4, in which, as in Figure 2, the center of the radio frequency car-

rier is assumed, for example, to be 104 megacycles.

Since the radio frequency carrier has a maximum deviation of 8 megacycles, the lower deviation limit is approximately 100 megacycles, whereas the upper deviation limit is approximately 108 megacycles. Since full black in the image (or the blanking impulses) normally has an intensity corresponding to 75% of the intensity of the peaks of the synchronizing impulses, the frequency corresponding to full black will be 106 megacycles.

With such a received radio frequency carrier (which corresponds to the received carrier in the conditions assumed in Figure 2), if a radio frequency oscillator operating at 90 megacycles is provided in the receiver, a frequency deviation of from 10 to 18 megacycles will be produced at the output of the mixer 10. At this point in the circuit two separate band pass amplifiers are provided, one of which is designed to accommodate the frequency deviations representing the image signals which extend from 10 to 16 megacycles, the other band pass amplifier being designed to accommodate at least a portion of the frequency deviations representing the synchronizing signals. These deviations extend from 16 to 18 megacycles. The first intermediate frequency amplifier 40, therefore, passes a band of frequencies extending from 10 to 16 megacycles, and after these signals have been properly amplified, they are then applied to an image discriminator which has a characteristic such as that represented in Figure 4 and which responds to the image signal deviations. At the output of the image discriminator image signals may then be derived which may have a wave form such as that represented by curve 52 in Figure 4.

It will be observed that the output from the image discriminator 44 does not include any synchronizing impulses, but includes only those signals which are representative of the particular television image frequency deviations. The frequency deviations that extend above 16 megacycles and which are a result of the transmission of the synchronizing signals are not impressed on the image discriminator 44 since they are attenuated by the intermediate frequency amplifier channel 40, its upper frequency limit being 16 megacycles.

Since any frequency deviation of the radio frequency carrier above 106 megacycles will normally extend to 108 megacycles, a certain portion of this frequency deviation may be eliminated. Accordingly, the synchronizing intermediate frequency amplifier 42 need not have a band sufficiently wide to accommodate the entire 2 megacycle deviation band from 16 to 18 megacycles, but may have a narrower band of approximately one megacycle preferably chosen to extend from 17 to 18 megacycles as shown in Figure 4. Under these conditions the synchronizing signal discriminator 48 need only be responsive to signals occurring within these limits, and such a discriminator may have a characteristic as that represented in Figure 4. At the output of the synchronizing signal discriminator are then available the synchronizing signals only, as represented by curve 54 in Figure 4.

There is a distinct advantage in limiting the band width of the synchronizing signal intermediate frequency amplifier 42 to frequencies occurring within the band of from 17 to 18 megacycles, since noise disturbances caused by static, automobile ignition, etc., are therefore at least in

part rendered ineffectual since the synchronizing signal band pass amplifier 42 is unresponsive to deviations occurring below 17 megacycles or above 18 megacycles. Since all synchronizing impulses normally produce a frequency deviation to approximately 18 megacycles in the intermediate frequency channel, the system will still respond to proper synchronizing impulses to produce at the output thereof a series of synchronizing signals which may be used for maintaining synchronous operation of the receiver with the transmitter.

By using a system such as that described above in connection with Figures 3 and 4, it may therefore be seen that a radio frequency carrier that has been frequency modulated by a standard composite video signal series may be conveniently received and applied to two separate intermediate frequency amplifier channels to result in complete and convenient separation of the synchronizing signals from the image signals.

Furthermore, under these conditions the band width of the intermediate frequency amplifier channels need not be excessively large, and, furthermore, the discriminators are not required to respond to an excessively wide frequency deviation band. The output from the image discriminator as represented by curve 52 in Figure 4 may be applied directly to an appropriate image amplifier 46, and after sufficient amplification the signal variation may then be applied to the control electrode of the image producing tube. No synchronizing separation circuits are necessary, since the separation is produced as a result of proper choice of intermediate frequency bands with the result that the output from the synchronizing signal discriminator 48 may be applied directly to the horizontal and vertical deflection generators used in the receiver.

The above assumed frequencies are for the purpose of explanation only, and it is obvious that any other range of frequencies or frequency deviation limits may be employed.

In explaining the systems shown in Figures 1 and 3, it is assumed that no frequency deviation occurs outside the prescribed deviation limits. Under actual operation it has been found that frequency deviations beyond the desired limits frequently occur, and in a system having band pass limits such as described above in connection with Figures 2 and 4, certain undesired effects will result. In order to describe these undesired effects, reference is now made to Figure 5 which shows a frequency discriminator response curve having substantially linear response characteristics between frequencies extending from f_0 to f_1 . The response of the discriminator falls off rapidly for frequencies below f_0 or above f_1 . With such a discriminator it is assumed that the video intermediate frequency band pass amplifier has a response characteristic such as that represented at 60, which, as may be seen from Figure 5, extends beyond the response band of the discriminator. If frequency deviations such as represented by curve 62 are applied to the intermediate frequency amplifier and discriminator, a voltage variation such as represented at 64 is available at the output of the discriminator. It will be noticed that the height of the synchronizing signal for curve 62 does not extend beyond frequency, f_1 , nor do any signals representing white extend below f_0 . In other words, the applied frequency deviation as represented by curve 62 is within the response limits of the discriminator, with the result that no distortion occurs and a proper voltage varia-

tion represented by the curve 64 will be produced at the output of the discriminator.

If, however, deviations beyond the limits of the discriminator are received at the receiver as represented by curve 66 of Figure 5, then certain undesired effects will result. If, for example, the synchronizing signal should for some reason deviate beyond frequency f_1 as represented by point A of curve 66, the discriminator output will 10 not correspond to the applied frequency deviation. This occurs by reason of the fact that the deviations extending beyond frequency f_1 , although wholly within the band pass limits of the intermediate frequency amplifier, are beyond the response characteristics of the discriminator, with the result that the output of the discriminator drops to zero rather than being a value such as represented by A' of Figure 5. The dotted portion 15 of the curve 68 of Figure 5 shows the voltage variation that would be available if the limits of the discriminator were sufficient to accommodate the extended frequency deviation, whereas the solid portion of the curve 68 represents the actual output from a discriminator having a characteristic represented by curve 58 of Figure 5. Since 20 the output of the discriminator falls to zero, such a signal potential would not be suitable for synchronizing purposes, but, instead, would correspond to a picture signal representative of gray. 25 Similarly, if the deviation in the direction of white extends below the deviation limit f_0 , then the discriminator response is such that the output signal is driven in the direction of black, as represented by the solid line in curve 68, rather than remaining 30 at point B', or at a value corresponding to full white in the image.

It will be seen, therefore, that if a television receiver employs an intermediate frequency band pass having sufficient width to accommodate appreciably more than the normal frequency deviation, but if the discriminator response will accommodate only the theoretical or prescribed frequency deviation, serious distortion of the wave form derived from the discriminator will result 40 if the frequency deviation of the signal remains within the intermediate frequency amplifier band width but extends beyond the discriminator frequency limits.

A similar undesired distortion results, as shown 50 in Figure 6, when the discriminator response is of sufficient width to accommodate excessive deviations, but where the video intermediate frequency band amplifier has a frequency limit only sufficient to accommodate the normal or prescribed frequency deviation. In this particular instance it will be assumed that the video intermediate frequency band accommodates only frequencies extending from f_0 to f_1 , as represented by curve 70 in Figure 6. It will also be assumed 55 that the discriminator has a wider deviation response ranging from below frequencies corresponding to f_0 and to above frequencies corresponding to f_1 . The curve of such a response is indicated at 72 in Figure 6.

65 If, under these conditions, the applied frequency deviations remain within the band from f_0 to f_1 , as represented by curve 74, then a corresponding and proper output voltage variation, as represented by curve 76, may be derived from the discriminator, since both the intermediate frequency amplifier and the discriminator will accommodate such a frequency deviation. Should the frequency deviation extend beyond these limits, however, as represented by curve 78 of Figure 6, distortion will occur, as shown in curve

80, since the voltage variation from the discriminator will be that represented by the solid rather than the dotted portion of curve 80. Should the synchronizing impulse extend beyond f_1 , as for example point C in Figure 6, then the output from the discriminator, instead of extending beyond black in the image as should be the case, will actually extend from black in the direction of white to a value corresponding to approximately zero voltage from the discriminator. The dotted portion C' shown at Figure 6, representing the synchronizing signal, will therefore be eliminated, and in the absence of such synchronizing signal the receiver may drop out of synchronization with the transmitter.

A similar situation will result if the frequency deviation in the direction of white in the picture extends below frequency f_0 , and as soon as the deviation extends beyond f_0 the voltage variation in the output from the discriminator will be abruptly driven toward zero rather than remaining of a value corresponding to white, or extending above white as shown at D', inasmuch as the band pass limits of the intermediate frequency amplifier channel have been exceeded.

Accordingly, if the video intermediate frequency band pass amplifier has a band width only sufficient to accommodate the normal frequency deviation limits, serious distortion will result should the deviation, for some reason, extend beyond these limits.

Since excessive frequency deviations cannot be entirely prevented, some provision must be made in the receiver for preventing serious distortion when such excessive deviation occurs. Obviously, if either the discriminator (as shown in Figure 5) or the intermediate frequency amplifier (as shown in Figure 6) will accommodate only frequencies occurring within the normal deviation band, distortion such as represented in Figures 5 and 6 will result. Such distortion may cause loss of synchronism, and where frequencies representative of white erroneously produce signals representative of black or gray in the image, considerable visible distortion will result in the produced television image.

In order to guard against such distortion, a receiver with components having response characteristics such as represented in Figure 7 may be used. In this figure it will be assumed that the normal deviation band extends from f_0 to f_1 for the complete video signal series. In this system two separate intermediate frequency amplifier channels are used, as shown and described in connection with Figures 3 and 4, with the normal image deviation extending from f_0 to f_2 and the synchronizing signal normal deviation extending from f_2 to f_1 . Since frequency f_2 is representative of black, the image intermediate frequency amplifier need not respond to any frequency above f_2 . Accordingly, the upper frequency limit of the image intermediate frequency amplifier band may coincide with frequency f_2 as indicated by curve 84 in Figure 7. Frequency deviations below frequency f_0 which correspond to full white in the image should be passed by both the intermediate frequency amplifier and the image discriminator in order to avoid the distortion represented at B' and D' in Figures 5 and 6, respectively. Accordingly, the lower frequency limit of the image intermediate frequency amplifier should extend an appreciable distance below f_0 .

The image discriminator may have a response such as indicated at 86 in Figure 7, and it is

preferable that the response be substantially linear between the limits of f_0 and f_2 . The response of the discriminator for frequency deviations above f_2 should remain at a value corresponding to the response at frequency f_2 to assure the production of a signal corresponding to full black in the image even though frequencies above f_2 cannot be passed through the image intermediate frequency amplifier. The discriminator should be responsive to signals below f_0 , and in order to prevent "blooming" on the image screen of the receiver, it is preferable that the response be maintained uniform for a predetermined amount below frequency f_0 , as indicated by curve 86. Accordingly, when frequency deviations representative of image signals are applied to an intermediate frequency amplifier having characteristics indicated by curve 84 and to a discriminator having characteristics indicated by curve 86, the distortion shown in Figures 5 and 6 will not occur. A frequency deviation such as represented by curve 88 of Figure 7 may be applied to these elements, and even though the deviation may sporadically extend below f_0 as indicated at E, the voltage output from the discriminator will remain at full white as represented at E' in curve 99, rather than drop to some value in the direction of black as in the case of Figures 5 and 6. Similarly, the presence of frequency deviations beyond f_2 (as occur during the synchronizing intervals) does not cause any change in the output signal strength from a value corresponding to full black.

In the synchronizing signal intermediate frequency amplifier it is not necessary that any frequencies below f_2 be passed since the frequency f_2 is representative of full black and all synchronizing signals extend in a direction above frequency f_2 . Accordingly, the synchronizing signal intermediate frequency amplifier may have a response such as indicated by curve 92 in Figure 7, with frequency f_2 representing the lower frequency limit and with the upper frequency limit extending appreciably above f_1 , in order to accommodate any excessive frequency swing in that direction.

Similarly, the synchronizing discriminator response may be such as represented by curve 94 in Figure 7, and should preferably be substantially linear between the limits of f_2 and f_1 , and should also be responsive to frequency deviations above f_1 in order to prevent elimination of the synchronizing signals as is the case in conditions represented by Figure 5 or Figure 6. The output from the discriminator should remain unchanged (at zero, for example) for deviations below f_2 , and since frequencies below f_2 cannot pass through the synchronizing signal intermediate frequency amplifier, as indicated at 92, the output potential level of the discriminator, in the absence of an applied signal, should correspond to its output when frequency f_2 is applied thereto.

If the frequency variations remain within the limits of f_2 and f_1 , then a normal synchronizing signal will be developed as represented by curve 96, and also if the deviation should exceed frequency f_1 as indicated at F in Figure 7, a proper synchronizing signal will still be derived from the discriminator since such excessive deviation is still within the pass band of the intermediate frequency amplifier and since the discriminator will respond, with substantially uniform output, to such excessive deviation. Accordingly, an excessive deviation in the direction of the synchro-

nizing signal will still produce a voltage variation at the output of the discriminator corresponding to the signal produced by a normal deviation.

Intermediate frequency amplifiers having the desired band width and characteristics may readily be designed in a manner well known to those skilled in the art. Furthermore, frequency discriminators of the desired band width and having characteristics such as represented by curves 86 and 94 in Figure 7 may also be provided by appropriate design and may, in fact, form a part of the intermediate frequency amplifier channels. For example, the image intermediate frequency amplifier channel may be designed as a low-pass filter having uniform response to frequencies below f_0 , and having a linear attenuating effect for frequencies between f_0 and f_2 . The response should be zero for frequencies above f_2 . When such an amplifier channel is provided, a frequency discrimination effect results between f_0 and f_2 . For the synchronizing intermediate frequency amplifier channel a high-pass filter circuit may be employed having zero transmission efficiency (or cut-off) below f_2 , a linear increase in response from f_2 to f_1 , and a uniform output response for frequencies above f_1 . Amplitude limiters may or may not be used in such a system, as desired.

When a television receiver is provided with image and synchronizing signal intermediate frequency band pass amplifiers such as represented by curves 84 and 92 in Figure 7, and when appropriate discriminators or frequency discriminating amplifiers are provided having characteristics such as represented by curves 86 and 94, it is possible to derive from the discriminator or frequency discriminating amplifier channels an image signal such as represented by curve 90 and a synchronizing signal such as represented by curve 96 without the distortion associated with circuit elements such as represented in Figures 5 and 6. The "clipping" action produced at E and F under conditions of excessive frequency deviation is desirable, since in the image signal such "clipping" action prevents "blooming" or the production of excessive white on the receiver screen as stated above.

Furthermore, the "clipping" action exercised on excessive deviation in the direction of the synchronizing signals is desirable, since the voltage variations derived from the synchronizing signal discriminator remains substantially uniform in intensity regardless of such excessive frequency deviation.

With the present invention it is, therefore, apparent that a television receiver may be provided which will respond to a frequency modulation of a radio frequency carrier where the frequency modulation is produced by a conventional composite video signal. It is also possible to utilize such a frequency modulated signal without resulting in undesired distortion and possible elimination of the transmitted synchronizing signals.

By exercising the present invention in conjunction with frequency modulated transmission of the accompanying audio signals, the television transmission may be made completely frequency modulated with desirable and satisfactory results at the receiver.

Although the present invention is described somewhat in detail, various alterations and modifications may be made therein without departing from the spirit and scope thereof, and it is desired that any and all such modifications be considered within the purview of the present in-

vention except as limited by the hereinafter appended claims.

Having now described our invention, what we claim as new and desire to have protected by Letters Patent is:

1. A television receiver for receiving a frequency modulated radio frequency carrier modulated by television video signals such that the frequency deviations representative of the image signals and the frequency deviations representative of the synchronizing signals occupy adjacent bands, comprising an image signal band pass amplifying channel having characteristics such that frequency deviations representative of the image signals may be amplified thereby, a frequency discriminator associated with said image signal amplifying channel, said discriminator having substantially linear frequency discriminating characteristics throughout substantially the entire image signal frequency deviation band and having substantially uniform response to frequencies outside the image signal frequency deviation band whereby television image signals may be produced by said discriminator, means for applying the produced image signals to a translating device, a synchronizing signal band pass amplifying channel having characteristics such that frequency deviations representative of the synchronizing signals may be amplified thereby, a second frequency discriminator associated with said synchronizing signal amplifying channel, said discriminator having substantially linear frequency discriminating characteristics over at least a portion of the synchronizing signal frequency deviation band and having substantially uniform response to frequencies outside the synchronizing signal frequency deviation band whereby television synchronizing signals may be produced by said second discriminator, and a synchronizing signal responsive circuit associated with said second discriminator.

2. A television receiver for receiving a frequency modulated radio frequency carrier modulated by television video signals such that the frequency deviations representative of the image signals and the frequency deviations representative of the synchronizing signals occupy adjacent bands, comprising an image signal amplifying channel having low-pass characteristics with uniform response below a predetermined carrier frequency corresponding to one frequency deviation limit of the image signals and with substantially linear diminution of response in the image signal frequency deviation band whereby at the output of said amplifier a series of image signals may be produced, a synchronizing signal amplifying channel having high-pass characteristics with uniform response above a predetermined carrier frequency corresponding to one frequency deviation limit of the synchronizing signals and with substantially linear diminution response in the synchronizing signal frequency deviation band whereby at the output of said synchronizing signal amplifier a series of synchronizing signals may be produced, and signal utilizing elements coupled to each amplifier circuit.

3. A television receiver for receiving a frequency modulated radio frequency carrier modulated by television video signals such that the frequency deviation band representative of image signals is adjacent the frequency deviation band representative of synchronizing signals, comprising a band pass image signal amplifying channel having a sloping characteristic such that sub-

stantially linear frequency response discrimination is present within the image signal frequency deviation band whereby at the output of said amplifier a series of image signals is produced, a band pass synchronizing signal amplifying channel having a sloping characteristic such that substantially linear frequency response discrimination is present within the synchronizing signal frequency deviation band whereby at the output of said synchronizing signal amplifier a series of synchronizing signals is produced, and translating devices individually responsive to the produced image and synchronizing signals.

4. A television receiver for receiving a frequency modulated radio frequency carrier modulated by television video signals such that the frequency deviation band representative of image signals is substantially adjacent the frequency deviation band representative of the synchronizing signals, comprising a first amplifying channel having low-pass characteristics with uniform response below a predetermined carrier frequency corresponding to the low frequency deviation limit of one frequency deviation band and with substantially linear decrease in frequency response within said one frequency deviation band whereby at the output of said amplifier a first series of signals is produced, a second amplifying channel having high pass characteristics with uniform response above a predetermined carrier frequency corresponding to the high frequency deviation limit of the other frequency deviation band and with substantially linear increase in frequency response within said other frequency deviation band whereby at the output of said second amplifier a second series of signals is produced, and signal utilizing elements coupled to each amplifier circuit.

mined carrier frequency corresponding to the high frequency deviation limit of the other frequency deviation band and with substantially linear increase in frequency response within said other frequency deviation band whereby at the output of said second amplifier a second series of signals is produced, and signal utilizing elements coupled to each amplifier circuit.
